UNITED STATES PATENT OFFICE.

LAWRENCE J. MONCRIEF, OF WINFIELD, KANSAS.

GRID LEAK.

Application filed October 31, 1923. Serial No. 671,977.

This invention relates to improvements in grid leaks for wireless apparatus.

An object of the present invention is the provision of a grid leak of simple construction, which may be connected directly with any of the terminals of a vacuum tube, so as to provide simple and convenient means for connecting the leak in an out-of-the-way position and at the same time provide a leak which may be connected in the circuit in the usual manner.

With the above and other objects in view, the invention further includes the following novel features and details of construction, to be hereinafter more fully described illustrated in the accompanying drawings and pointed out in the appended claims.

In the drawings:-

Figure 1 is a bottom plan view of a vacuum tube with the leak in position.

Figure 2 is a similar view showing the leak engaged with different terminals of the tube.

Figure 3 is a plan view of the grid leak looking at the side opposite that shown in Figures 1 and 2.

Figure 4 is an edge view of the grid leak.

Figure 5 is a section on the line 5—5 of Figure 3.

Figure 6 is a section on the line 6—6 of Figure 3.

Figure 7 is a detail view of one of the binding strips.

Figure 8 is a plan view of a modified form of the invention.

Referring to the drawings in detail wherein like characters of reference denote corresponding parts, the reference character V indicates a vacuum tube whose plate terminal is indicated at P, grid terminal at G and filament terminals at F and F', one being the positive and the other the negative filament terminal.

The grid leak which is indicated generally at L comprises a base 10 which is formed of some suitable insulating material such as bakelite. This base is provided with openings 11 and 12, the latter being relatively large. The base is further provided at one end with a notch 13 which is in alignment with the openings.

Mounted upon the base between the openings 11 and 12 is a strip of high resistance material 14, the said strip being held in place by means of copper binding strips 15. These strips 15 extend transversely across the base

over the ends of the resistance material 14 and are provided with openings 16 for register with the openings 11 and 12 of the base. In order to provide openings upon opposite sides of the base, the ends of the strips are provided with semi-circular notches 17 so as to form proper size openings when the strips are in position.

Over the meeting ends of the strips 15 there is placed a plate 18 of insulating material which is of the same shape and size as the base 10 and which may be secured to the base by means of shellac or other adhesive material. If desired a sheet of mica 19 may be placed over the resistance material 14 for the protection of the latter. The base 10 and the plate 18 are relatively thin, the said plate 18 which may also be formed of bakelite or other insulating material, may be thinner than the base 10 as it merely forms a cover for the resistance material 14.

Secured to the strips 15 by means of hollow rivets 20 are spring contact members 21 and 22. These members may be of any suitable type, but it is preferred to form them of spring brass shaped to provide rings 23 which surround the openings 16, while projecting from these rings are fingers which are bent to provide the spring contact members 21 and 22 previously mentioned. The finger which forms the contact member 22 may be relatively long and shaped so as to extend over both the opening 11 and the notch 13.

The grid leak constructed in the manner just described may be engaged over the tube terminal G and the tube terminal F as shown in Figure 1 so that the said terminals will engage the spring contacts 21 and 22. If desired, the leak may be engaged over the tube terminal G and the tube terminal F' as shown in Figure 2. It will thus be possible to connect the grid, through the leak, to either terminal of an "A" battery so as to place either a positive or a negative charge upon the grid. The opening 12 is of greater diameter than the opening 11 so as to adapt the leak to different tubes in which the distance between the terminals may slightly vary.

The form of the invention shown in Figure 8 is substantially the same as that just described except that the cover plate 18 is omitted and the high resistance is formed in separate sections 23' and 24. These sections are spaced apart and may be electrically

connected by any desired means such as by means of an ordinary pencil line 25, the thickness of which may vary to provide a variable leak.

5. The invention is susceptible of various changes in its form, proportions and minor details of construction and the right is herein reserved to make such changes as properly fall within the scope of the appended claims.

10. Having described the invention what is claimed is:—

1. A grid leak comprising a base formed of insulating material, means whereby the base may be removably engaged over the 15 terminals of a vacuum tube, a resistance element carried by the base and means whereby the resistance element may be electrically connected to the tube terminals.

2. A grid leak comprising a base formed 20 of insulating material, means whereby the base may be engaged with the terminals of a vacuum tube, a resistance element carried by the base and yieldable contact members electrically connected to the resistance element for engagement with the tube terminals.

3. A grid leak comprising a base formed of insulating material, means whereby the base may be removably engaged over any 30 two terminals of a vacuum tube, a resistance element carried by the base and means whereby the resistance element may be electrically connected to the tube terminals.

4. A grid leak comprising a base formed 35 of insulating material and provided with spaced openings for receiving the terminals of a vacuum tube, a resistance element carried by the base and means whereby the resistance element may be electrically connected to the tube terminals.

5. A grid leak comprising a base formed of insulating material and provided with spaced openings and a notch in one end thereof for receiving the terminals of a 45 vacuum tube, a resistance element carried by the base and means whereby the resistance element may be electrically connected to the tube terminals.

6. A grid leak comprising a base formed 50 of insulating material and provided with spaced openings for receiving the terminals of a vacuum tube, a resistance element carried by the base and means including yield-

able contact members extending from the openings for engagement with the tube terminals, whereby electrical connection may be established between the tube terminals and the resistance element.

7. A grid leak comprising a base formed of insulating material and provided with spaced openings and a notch in one end thereof for receiving the terminals of a vacuum tube, a resistance element carried by the base and means including yieldable 60 contact members extending over the openings and notch, whereby electrical connection may be established between the tube terminals and the resistance element.

8. The combination with a vacuum tube, of a grid leak and means whereby the grid leak may be directly secured over the contact terminals of said tube.

9. The combination with a vacuum tube, of a grid leak and means whereby the grid leak may be removably secured over the 75 terminals of said tube so that either positive or negative current may be placed upon the tube grid.

10. The combination with a vacuum tube, of a grid leak having spaced openings there- 80 in to receive the contact terminals of a tube, one of said openings being of a relatively large diameter to compensate for differences of spacing between the contact terminals of different tubes.

11. A grid leak comprising a base formed of insulating material and provided with openings spaced to receive the contact terminals of a vacuum tube, a resistance element shaped to conform to the shape of the base, 90 metallic bands surrounding the base and resistance element and engaging the latter to provide a conductor, said bands having openings therein registering with the openings of the base and resistance element, an insulating plate engaging the bands adjacent the resistance element and also provided with openings, hollow rivets extending through the openings of the base, resistance element, bands and plate to receive the contact terminals of a vacuum tube and contact members extending from the rivets for engagement with said terminals.

In testimony whereof I affix my signature.

LAWRENCE J. MONCRIEF.
